C. E. L. LIPMAN

COMPRESSOR

Filed Sept. 26, 1921

UNITED STATES PATENT OFFICE.

CARL E. L. LIPMAN, OF BELOIT, WISCONSIN, ASSIGNOR TO LIPMAN REFRIGERATOR CAR & MANUFACTURING COMPANY, OF BELOIT, WISCONSIN, A CORPORATION OF DELAWARE.

COMPRESSOR.

Application filed September 26, 1921. Serial No. 503,255.

To all whom it may concern:

Be it known that I, CARL E. L. LIPMAN, a citizen of the United States, residing in Beloit, in the county of Rock and State of Wisconsin, have invented certain new and useful Improvements in Compressors, of which the following is a specification.

This invention relates in general to compressors and has more particular reference 10 to a compressor adapted to be used as an ammonia compressor in refrigerating systems and other places where ammonia compressors are utilized.

In a compressor of this type which is 15 subjected to practically continuous usage for long periods of time, it is essential that provision for adequate lubrication of the working parts be made and also that leakage of the ammonia be effectually prevented. 20 Furthermore, I have found that it is very detrimental to the successful operation of an ammonia system if oil be permitted to enter the system and become mingled with the ammonia.

One of the primary objects of my present 25 invention is to provide a compressor which will efficiently compress ammonia gas and which will preclude the leakage or escape of the gas and will also provide for adequate lubrication of the compressor and at the 30 same time prevent the lubricating oil from entering the ammonia system.

For the purpose of facilitating an understanding of my invention, I have shown on 35 the accompanying drawing one preferred embodiment thereof, from an inspection of which, when considered in connection with the following description, my invention and many of its inherent advantages should be 40 readily understood and appreciated.

Figure 1, is a vertical sectional view 45 through a compressor embodying my invention; and

Fig. 2, is a plan view of the piston cross-head 44, removed from the compressor.

It will be observed that the compressor 50 comprises an upright hollow casting 1, formed at its bottom to provide a suitable base or pedestal 2, the casting being open from side to side to permit the introduction thereinto of the crank shaft 3 equipped with the crank 4.

The outer end of the crank shaft is supported in a bearing 5 formed in the cap 6

which provides a closure for one side of 55 the main casting to which it is securely attached by lag bolts 7. The shaft at the opposite side of the crank is supported in a bearing 8 carried by the closing plate 9 which forms a closure for the main casting 60 at that side of the machine, this plate being secured to the main casting by lag bolts 11. The shaft projects outwardly thru this member 9 as shown, and a stuffing box 12 is utilized to seal the opening around the shaft 65 and prevent escape of the oil from the crank case along the shaft. Power is applied to shaft 3 to rotate the crank, at a point outside the crank case where the shaft may be equipped with a belt pulley or may be directly connected to a motor if preferred. It will thus be manifest that I have provided a crank case which is entirely closed and which may be filled with oil to provide adequate lubrication for the moving parts. 75

The upright casting 1 carries a tubular crosshead guide indicated by reference character 13 which snugly fits within the upright casting 1 into which it is inserted from the upper end thereof. A plurality of screw 80 bolts 14 threaded thru the side of the upright member 1 and engaged at their inner ends in a circumferential groove 15 formed in the member 13 serve to securely lock the member 13 in position.

The piston cylinder consists of a member 16 shaped at its lower end to snugly fit within the upright member 1 and adapted to rest upon the upper end of the upright member to which it is securely attached by bolts 90 17 leakage between the members being precluded by a packing ring 18. The member 16 is centrally bored to provide the cylinder in which the piston reciprocates and is bored to form a surrounding chamber 19 adapted 95 to contain a circulating cooling medium, thereby serving the same function as a water jacket of a gas engine. The top of the cylinder proper is closed by a cap 21 which is shaped on its inner face to provide a guide 22 for the stem 23 of the exhaust valve 24 which is urged against its seat 25 formed in the member 16 by a coiled expansion spring 26. The upper end of the water chamber is closed by a cap plate 27 secured 100 by bolts 28 to the outer wall of the member 16. Exhaust port 29 extends radially from the cylinder above the valve 24 and a

pipe 31 connected with this port serves to conduct the compressed ammonia to the condenser of the system.

The piston 32 is adapted to reciprocate within the cylinder bore, leakage around the piston being precluded by rings 33. The inlet valve 34 is carried by the piston and is normally urged against its seat by a coiled spring 35 surrounding the valve stem 36 which is guided in a spider 37 and a guide 38 as shown. Passage 39 formed in the main member 1 surrounds the cylinder beneath the piston and communication is established between this passage and the interior of the cylinder thru a series of radial ports 41. The inlet pipe 42 leading from the absorber of the system is connected with the chamber 39 so that the incoming gas passes from the pipe 42 into the chamber 39 and thence thru the ports 41 into the cylinder beneath the piston.

The piston is actuated by a rod 43 connected at its upper end to the piston and at its lower end to an open guide or crosshead 44 adapted to reciprocate in the crosshead guide 13, this guide in turn being reciprocated from the crank 4 by a connecting rod 45. It will be observed that the guide 44 serves to maintain the lower end of the rod 43 in absolute alinement with the axis of the cylinder so that radial or angular movements of the piston which might result in undue wear or leakage, are obviated. It will be further observed that the crosshead is open from end to end as indicated by reference numeral 44' at each side of the connecting rod pin and the diametrical spider into which the lower end of the rod 43 is threaded, as shown by the openings 44', Fig. 2, thus allowing oil from the crank case to splash up through said openings to lubricate the walls of the crosshead guide, and also to lubricate the rod 43.

In order to preclude the oil in the crank case from working up into the upper cylinder where it would become mixed with the ammonia gas entering thru the pipe 42, I have provided a seal between the piston and its guide which serves to prevent the upward passage of the oil and also to a large extent prevents the ammonia gas from passing downwardly into the crank case altho escape of the gas downwardly into the crank case is not materially detrimental since the crank case is entirely closed and effectually sealed against the escape of either oil or gas out into the atmosphere.

The seal between the piston and the crosshead 44 consists of a stuffing box formed by a lower member 46, an upper member 47 and interposed packing material 48 surrounding the guide rod 43. The lower member 46 of the stuffing box is attached by screws 49 to the upper end of the member 13 before the upper cylinder member 16 is as-

sembled with the upright member 1. The upper member 47 is continuously urged toward the member 46 to maintain the packing material 48 under compression by means of coiled expansion springs 51 interposed between the member 47 and the heads of elongated screws 52 passing loosely thru apertures in the margin of member 47 and threaded into tapped openings in member 46. It will thus be manifest that by this construction I have provided an effectual seal between the ammonia system and the crank case of the compressor.

In the operation of the machine, ammonia gas is drawn into the cylinder beneath the piston upon the up stroke of the piston, and upon the down stroke it passes thru the piston around the valve 34. A check valve (not shown) in the pipe 42 serves to prevent the gas from backing up into the absorber. Upon the up stroke of the piston the gas is compressed and finally expelled past the valve 24 and out thru the pipe 31 to the condenser.

From the foregoing it will be observed that I have provided a compressor in which ammonia gas is effectually prevented from escaping, and loss of lubricant from the crank case through the compressor cylinder and the circulating ammonia is likewise effectually prevented. This result is obtained by a combination of elements provided by the construction disclosed herein, to certain phases of which attention will now be more particularly directed. It will be noted that both the crank case chamber and the chamber in which the crosshead 44 reciprocates are closed to the atmosphere and sealed from the piston cylinder by the stationary packing device comprising in this instance the members 46 and 47 and the interposed packing as described above. By closing both said chambers to the atmosphere I am enabled to employ a comparatively small packing on the rod 43 because this packing or sealing device functions primarily for keeping oil from entering the piston cylinder rather than being of such large proportions and requiring such heavy pressure and tight seal as to prevent the escape of ammonia fumes to the chambers below. Consequently friction and wear on this packing is reduced and it is comparatively long-lived for the purpose intended. The incidental escape of ammonia fumes to the chambers below is not detrimental because such chambers are structurally closed to the atmosphere. In fact the only possible escape is through the stuffing box 12 and this is effectually precluded not only by the function of the packing but by an oil seal provided by maintaining an oil level in the crank case above the crank shaft bearings. This liquid seal is very effective in preventing leakage of ammonia gas through the stuffing box, espe-

cially inasmuch as the pressure in the crank case is comparatively low. This oil level will be maintained over a long period without replenishing because the oil consumption is very low due to the means provided herein against loss.

It will be further observed that this method makes for greater practicability in compressors of this type because these compressors are used to a great extent in domestic refrigeration systems. Escape of ammonia fumes from such compressors is obviously very objectionable. The present invention provides in a comparatively simple and practical way for preventing such leakage; and it will be observed that in addition to closing the crosshead chamber and the crank shaft chamber to the atmosphere and providing packed joints at the only two outlets, I have further reduced the chance for escape by utilizing an oil seal for the crank shaft packing, as shown in Fig. 1. The packing against a rotating part such as the crank shaft will maintain a much tighter seal than the smaller packing against a reciprocating part such as rod 43, consequently even though the oil level should drop in the crank case the liability of fumes escaping is reduced to a minimum. Adequate lubrication of the crosshead guide walls is also effected in a simple and practical manner, especially by reason of the enclosed crosshead chamber and the provision for splash lubrication through the crosshead. And inasmuch as all working parts are closed from the outer atmosphere all dust, dirt and other foreign matter is excluded, thus further aiding in the general efficiency of compressors of this type.

From the foregoing it will be manifest that my invention in its broader aspect contemplates a suitable casing providing a cylinder for the ammonia pumping piston and a crosshead cylinder or guide in axial alignment and a crank case communicating with said guide, all of which are structurally closed to the atmosphere, and in which a stationary sealing device separates the piston cylinder and the chamber in which the crosshead reciprocates and surrounds and embraces the rod connecting the crosshead and piston so as to provide circumferential contact with the said rod.

It is believed that my invention, its mode of operation, and many of its attendant advantages will be understood and appreciated from the foregoing without further description, and it should be manifest that the details of construction shown and described are capable of considerable modification without departure from the essence of the invention as defined in the appended claims.

I claim:

1. In a compressor, the combination of a hollow member forming at one end a por-

tion of a closed crank case, a cylinder carried by said member and provided with inlet and outlet ports, a crosshead guide carried by said member between said cylinder and the crank case, a crosshead reciprocable in said guide, a piston reciprocable in said cylinder, a rod connecting said crosshead with said piston, and a stationary sealing device surrounding and embracing said rod for preventing leakage between the cylinder and the crank case, said crosshead being open to permit the passage of oil therethrough to lubricate said rod and the walls of said guide.

2. In a compressor, the combination of a cylindrical member having a transverse opening through its lower end forming part of a closed crank case, means closing the ends of said opening to seal said crank case, a crank in said case, a cylindrical guide mounted in said member just above said crank case, an open crosshead reciprocable in said guide by said crank, a cylinder rigidly mounted upon and extending into the upper end of said member, the space between said cylinder and said guide being enclosed by the walls of said member, a piston reciprocable in said cylinder, a rod connecting said piston with said crosshead, and a stuffing box disposed within said member and through which said rod extends, whereby the cylinder is sealed from the crank case, lubrication of said rod from the crank case being permitted through said open crosshead.

3. A compressor comprising, in combination, a casing structure providing a piston cylinder, a cylindrical guide and a crank case, the cylinder and guide being coaxial and the guide being interposed between the cylinder and crank case, the cylinder having an inlet and an outlet portion, a piston reciprocable in the cylinder, a crosshead reciprocable in the cylindrical guide, a rod connecting the crosshead and piston, a crank shaft journaled in the crank case and connected by a connecting rod to the crosshead, a stationary sealing device interposed between and separating the cylinder and chamber in which the crosshead reciprocates, said device surrounding and embracing the piston rod and having a circumferential sealing contact thereabout, one end of the crank shaft extending beyond the crank case for connection to a driving means, a stuffing box for said end of the crank shaft, the crank shaft chamber and the crosshead chamber being structurally closed to the atmosphere, whereby to effectually prevent escape to the atmosphere of gases being pumped by the compressor and to prevent loss of oil from the crank case through the compressor cylinder.

4. A compressor comprising, in combination, a casing structure providing a piston cylinder, a cylindrical guide and a crank

- case, the cylinder and guide being coaxial and the guide being interposed between the cylinder and crank case, the cylinder having an inlet and an outlet portion, a piston reciprocable in the cylinder, a crosshead reciprocable in the cylindrical guide, a rod connecting the crosshead and piston, a crank shaft journaled in the crank case and connected by a connecting rod to the crosshead, a stationary sealing device interposed between and separating the cylinder and chamber in which the crosshead reciprocates, said device surrounding and embracing the piston rod and having a sealing contact thereabout, one end of the crank shaft extending beyond the crank case for connection to a driving means, a stuffing box for said end of the crank shaft, the crank shaft chamber and the crosshead chamber being structurally closed to the atmosphere, whereby to effectually prevent escape to the atmosphere of gases being pumped by the compressor and to prevent loss of oil from the crank case through the compressor cylinder, the crosshead being open from end to end to permit oil from the crank case to splash up into the crosshead chamber for lubricating the guide wall thereof.
5. An ammonia compressor comprising, in combination, a casing structure providing a piston cylinder, a crank case and an interposed crosshead guide chamber, an ammonia pumping piston reciprocable in the cylinder, a crosshead reciprocable in the guide chamber and guided by the walls thereof, a rod connecting the crosshead and piston, a crank shaft journaled in the crank case and connected by a connecting rod to the crosshead, a stationary sealing device separating the piston cylinder and the crosshead guide chamber and including a packing surrounding and embracing the piston rod and providing circumferential sealing contact therewith, and the crank case and crosshead guide chamber being structurally closed to the atmosphere, whereby to prevent escape of ammonia fumes into the atmosphere and to prevent loss of oil from the crank case through the ammonia cylinder.
6. A vertical ammonia compressor comprising, in combination, a casing structure providing a piston cylinder and a cylindrical crosshead guide in vertical alignment and a crank case communicating with the lower end of the chamber formed by the crosshead guide, an ammonia pumping piston reciprocable in the cylinder, a crosshead reciprocable in the guide, a rod connecting the piston and crosshead, a stationary sealing device interposed between and separating the piston cylinder and guide chamber and surrounding and embracing the piston rod and having circumferential sealing contact therewith, a crank shaft journaled in the crank case and connected by a connecting rod to the crosshead, one end only of the crank shaft extending beyond the crank case, a stuffing box between said extended end of the crank shaft and the crank case, the crank case chamber and the crosshead guide chamber being structurally closed to the atmosphere, and an oil seal for the stuffing box, whereby to prevent leakage of ammonia fumes to the atmosphere and to prevent loss of oil through the piston cylinder.

CARL E. L. LIPMAN.
